UNITED STATES PATENT OFFICE.

GEORGE B. SPRING, OF WEST NEWTON, MASSACHUSETTS.

POLE REINFORCEMENT.

Application filed November 15, 1926. Serial No. 148,364.

This invention relates to means for reenforcing telephone poles, telegraph poles and other transmission poles. Poles which are used for telephone or for telegraph lines or other transmission lines are usually of wood and they have the disadvantage that after a few years' use they become weakened by decay at or just below the surface of the earth. It has been proposed to reenforce a weakened pole by placing in the earth alongside of the pole one or more reenforcing members which are clamped to the pole above the earth. If, however, the pole is quite badly weakened by decay it may have little or no strength at the weakened portion to resist swaying movement of the pole and in such case the swaying movement of the pole must be resisted entirely by the reenforcing members. Some types of reenforcing members are adapted to be driven into the earth alongside of the pole and these are not anchored to the butt of the pole below the earth's surface but only to the pole above the earth's surface. If a reenforcing member of this type is applied to a pole which is badly weakened by decay so that it has little or no strength at the weakened portion practically the entire force which is available to resist swaying tendency of the pole is the resistance of the earth against the portion of the reenforcing members that are embedded in the earth and if this resistance is not sufficient for the purpose there is likelihood that if the pole is subjected to severe strain tending to sway it laterally the reenforcing members will be tipped out of the earth leaving the butt of the pole still embedded in the earth.

One of the objects of my invention is to provide an improved reenforcement by which the earth resistance of the butt portion of the pole may be used to prevent swaying of the pole even though the pole is badly weakened and has practically no strength at the decayed portion. This object is accomplished by providing a reenforcing member which is constructed so that it has sufficient interlocking engagement with the pole butt so that any lateral strain to which the reenforcing member is subjected by the swaying of the pole will be transmitted to the butt and will thus be resisted by the earth resistance against the butt. In the preferred embodiment of my invention this is accomplished by providing the reen-

forcing member with a fin of considerable extent constructed so that when the reenforcing member is driven into the earth alongside of the pole said fin will acquire its interlocking engagement with the pole. 60 With this construction, therefore, there is no danger that the reenforcing members will be tipped out of the earth by the lateral swinging movement of the pole due to lack of earth resistance against the reenforcing 65 members because the full earth resistance against the butt of the pole is available for holding the reenforcing members in place.

Another object of the invention is to provide an improved form of reenforcing member which may be used either with the butt which the pole originally had when it was set or with a substitute butt which may be placed in position to receive a broken pole. 70

Other objects of the invention are to improve generally a pole reenforcement in various particulars all as will be more fully hereinafter set forth. 75

In the drawings wherein I have illustrated some selected embodiments of my invention 80 Fig. 1 is a side view of a pole reenforcement embodying my invention;

Fig. 2 illustrates the manner in which one of the reenforcing members is inserted in place; 85

Fig. 3 is a view of one of the reenforcing members;

Fig. 4 is a section on the line 4—4, Fig. 1;

Fig. 5 is a section on the line 5—5, Fig. 1;

Fig. 6 is a view showing a different embodiment of the invention; 90

Fig. 7 is a view showing the manner of applying the reenforcement shown in Fig. 6 to a pole;

Fig. 8 is a section on the line 8—8, Fig. 6; 95

Fig. 9 is a view of a spacer which may be used between the pole body and the butt;

Fig. 10 illustrates a different embodiment of the invention.

Fig. 11 is a fragmentary view illustrating 100 the fin at the lower end of the reenforcing member.

Referring first to Figs. 1 and 2 of the drawings 1 indicates a wooden pole such as would be used for telephone or telegraph lines or other transmission purposes and which is set into the earth 2. These wooden poles soon become weakened by decay at the surface of the earth as indicated at 3.

The pole reenforcement herein shown is 110

of that type comprising one or more reenforcing members which are adapted to be driven or set into the earth alongside of the pole. In Fig. 1 I have shown two such 5 reenforcing members, they being indicated at 4. Each is provided at its upper end with a thickened head portion 5 to receive the hammer blows by which the reenforcement is driven into the earth alongside of 10 the pole. Said reenforcing member is shown as having a central longitudinally-extending earth-resisting rib 6 which is of considerable width at about the surface of the earth but which is of less width toward 15 the ends.

The reenforcing member or members are clamped to the pole above the surface of the earth by clamps which are similar in some respects to those shown in my co-pending 20 applications Serial No. 50,319, filed August 14, 1925 and Serial No. 110,661, filed May 21, 1926. These clamping members each comprise a perforated connecting plate 7 and clamping rods 8 that connect the plate to 25 the reenforcing members. Where two reenforcing members are employed said members will be connected by a plurality of clamping devices each comprising a perforated plate 7 and the clamping rods 8. Each clamping rod is formed at its inner end with a head 30 9 (preferably a pointed head) which engages the inside of the plate 7, said clamping rod then being bent as shown at 10 and extending to and through an aperture in the rib 6 of the reenforcing member, the clamping rod having a clamping nut 11 screw-threaded thereon by which the reenforcing members may be firmly clamped against the pole. The heads 9 not only prevent the 35 clamping rods 8 from pulling out of the apertures in the plate but because of their pointed shape they become embedded in the pole body somewhat as shown in Fig. 5 and thus assist in holding the pole rigidly in 40 position.

In case the pole is badly weakened so that it has little or no strength at the weakened portion 3 then with the construction illustrated in the above-mentioned applications 50 the only force to prevent the pole from being blown over or from swinging laterally is the earth resistance against the reenforcing members. If the earth is of a sandy or loose nature this earth resistance of itself 55 may not be sufficient for this purpose in which case the reenforcing members are apt to be tipped out of the ground.

One of the objects of my invention is to 60 provide a novel construction by which the earth resistance against the butt 12 of a pole may be added to the earth resistance of the reenforcing members in holding the pole in proper position. This is accomplished herein by providing each reenforcing

member with a web or fin 13 which is embedded in the butt 12 of the pole and which has sufficient extent and strength and a sufficient interlocking engagement with the butt of the pole to transmit thereto the strain exerted on the reenforcing members by any 65 swaying or tipping tendency of the pole. With this construction whenever there is a strain on the pole tending to swing or tip it laterally this strain is transmitted to the reenforcing members because of their being 70 clamped to the pole above the earth and because of the interlocking engagement between the fin 13 of considerable extent and the butt of the pole this strain will be transmitted to the pole butt. Thus in this arrangement the earth resistance of the butt 12, which is a very considerable amount, is added to that of the reenforcing members 4 in resisting the swaying tendency of the pole and this would be the case even though the 80 pole were badly weakened at the point 3 or were perhaps broken at this point.

The fins 13 are preferably formed so that as the reenforcing members are driven into the earth they will automatically become embedded in the pole. Each fin 13 is preferably formed with a pointed nose 14 and with a V edge 15, said edge 15 being curved slightly toward the point 14 so as to form a 85 sort of beak.

As stated above these reenforcing members are intended to be driven into the earth alongside of the pole, as indicated in Fig. 2, and as they are thus driven the beak or nose 14 will plow its way into the side of 90 the pole as shown in Fig. 2, the shape of the nose 14 and the inclined face 16 together with the pressure of the earth against the reenforcing member tending to prevent the fin from working out of the pole. As the 95 reenforcing member is driven, therefore, the fin 13 plows a sort of groove or furrow in the pole. This may be done by simply opening up a groove in which the fin is received or by the fin throwing out a chip as indicated at 17. This would depend upon the 100 character of the pole. In any event, however, when the reenforcing member is driven home, as shown in Figs. 1 and 2, the lower 105 end thereof is interlocked with the lower end of the butt 12 of the pole and any strain on the reenforcing members tending to tip the lower ends out of the earth will be transmitted to the butt 12 which will add its 110 earth resistance to that of the reenforcing members. In driving the reenforcing members into the earth as shown in Fig. 2 a chain or flexible connection 18 will preferably be placed around the pole and reenforcing member so as to hold the latter 115 120 hugged tightly to the pole.

The rib 6 of the reenforcing member is 125 formed with a relatively wide portion 19

just below the surface of the earth so that a large earth resistance at this point is provided for.

In the construction above described the 5 reenforcing members are used and interlocked with the butt 12 which the pole originally had when it was set. My invention is also applicable for use in strengthening and reenforcing a pole where the original pole 10 butt is removed and another one substituted therefor as might be desirable in case the original butt is badly decayed. Sometimes the decay in a pole reaches clear to the bottom of the butt. In such case it may be 15 desirable to cut the pole off at the surface of the earth, removing the butt 12 which formed a part of the original pole and then substituting another butt therefor.

A construction of this sort is shown in 20 Figs. 6 and 7. In reenforcing a pole in this way the pole will be sawed or cut off at about the surface of the earth and then the original pole butt will be removed. This may be done by digging the earth away around 25 the butt as shown at 20, Fig. 7. Another pole butt 21, which may be wood treated with creosote or any other way to resist decay, or may be a concrete butt if desired, is then placed in the hole 20 and the reenforcing 30 members placed in position alongside of the butt. The substitute pole butt 21 will be formed with recesses in its side to receive the fins 13.

It may be desirable under some circumstances to clamp or bolt the reenforcing members to the substitute butt 21. Each reenforcing member is shown as having one or more bolt holes 22 at its lower end and one or more bolt holes 23 midway of its 40 length, these bolt holes being adapted to receive clamping bolts 24, 25 that extend through the substitute butt. Where the clamping bolts are thus used I propose to insert the clamping bolt 24 and clamp the 45 lower ends of the reenforcing members firmly to the substitute butt before the latter is inserted into the hole 20. The upper clamping bolts 25 will be left loose so that the upper ends of the reenforcing members 50 may be spread slightly. After the substitute butt with the reenforcing members secured thereto is placed in the hole the earth may be tamped around the lower end thereof and then the pole body may be placed between the upper spread ends of the reenforcing members, the spread condition of said ends 55 permitting the pole body to be readily inserted in place. When the pole is in place the clamping bolts 25 are tightened and the clamps 7, 8 are applied. With this construction the pole will be as firmly held as with the construction shown in Figs. 1 and 2 because notwithstanding the fact that the pole body is severed from its butt yet the pole 60

body is firmly clamped to the reenforcing 65 members and the latter in turn are firmly clamped to the butt 21 and hence a rigid pole structure is produced.

I will preferably arrange the substitute butt 21 so that it comes to the surface or 70 slightly above the surface of the earth and I propose to insert a spacing member 26 between the substitute butt and the lower end 75 of the pole body. This spacing member is shown as in the form of a ring having V upper and lower edges which become embedded somewhat into the pole body and the substitute butt, if the latter is of wood. This spacing ring is shown as having 80 notches or openings 27 to provide drainage and ventilation.

If desired I may make the reenforcing members with other fins 28 which are adapted to enter recesses formed in the butt 21 thereby to form an added interlocking between the butt and reenforcing members. 85 If these extra fins 28 are employed it may not be necessary to use the clamping bolts 25 as the fins will prevent lateral movement between the butt 21 and the reenforcing 90 members. The use of the fins 28 is optional, however, as well as the use of the upper clamping bolt 25. Furthermore, if desired I may make the reenforcing members with more than one fin 13, one or more 95 added fins being used on each reenforcing member above the lower fin.

It will be noted that the V edge 15 of each fin 13 is cut away as shown at 29. The purpose of this is so that in case the fin 100 strikes a knot or other obstruction and gets crowded out of the pole it will more quickly re-enter the pole as it is driven, said fin being allowed to re-enter as soon as the re-enforcing member has been driven to a point 105 where the knot or other obstruction passes into the cutaway portion 29 of the edge.

I claim:

1. The combination with a pole, of a re-enforcing member set into the earth alongside of the pole and extending above the earth, and means for clamping said re-enforcing member to the pole above the earth, said re-enforcing member having on its lower end a fin of considerable dimension radially 110 of the pole which is embedded in the butt of the pole, whereby the full earth resistance of said butt is added to that of the re-enforcing member in overcoming swaying 115 tendency of the pole.

2. The combination with a pole, of a re-enforcing member adapted to be driven into the earth alongside of the pole, means for clamping said re-enforcing member to the pole above the earth, said re-enforcing member having at its lower end on its pole-engaging side a fin formed with a beak portion, whereby as the re-enforcing member is driven 125

the beak will plow into the butt of the pole and the fin will become interlocked with the pole.

3. The combination with a pole, of reenforcing members placed in the earth alongside of the pole and means for clamping said members to the pole, said clamping means comprising perforated plates and clamping dogs adjustably securing the plates to the 10 reenforcing members, each dog having an inturned end extending through an aperture in the plate and a head at the terminus of said inturned end engaging the inside of the plate, said head having a conical exterior 15 face which is embedded in the pole by the clamping pressure.

4. The combination with a pole, of reenforcing members placed in the earth alongside of the pole and means for clamping said members to the pole, said clamping 20 means comprising perforated plates and clamping dogs adjustably securing the plates to the reenforcing members, each dog having an inturned end extending through an aperture in the plate and a pointed head at the terminus of said inturned end, which head engages the inside of the plate, the point of the head being embedded in the pole by the clamping pressure.

In testimony whereof, I have signed my 30 name to this specification.

GEORGE B. SPRING.
